UNITED STATES PATENT OFFICE.

WILLIAM H. FRICK, OF PHILADELPHIA, PENNSYLVANIA.

REAMER.

1,243,502.

Specification of Letters Patent.

Patented Oct. 16, 1917.

Application filed July 19, 1916, Serial No. 110,149. Renewed August 23, 1917. Serial No. 187,889.

To all whom it may concern:

Be it known that I, WILLIAM H. FRICK, a citizen of the United States, residing at Philadelphia, in the county of Philadelphia and State of Pennsylvania, have invented 5 new and useful Improvements in Reamers, of which the following is a specification.

This invention relates to machinists tools and refers especially to devices employed 10 for truing and enlarging holes and commonly designated as reamers.

The object of the invention is to provide a reamer having rotatable cutting members which may be readily applied and removed 15 for sharpening or repairs, uniformly and simultaneously adjusted relative to the axis of the device, and in which simple and efficient means are furnished for adjusting the cutters and clamping the same in position 20 when adjusted.

The invention consists of the features of construction, combination and arrangement of parts hereinafter fully described and claimed, reference being had to the accompanying drawing in which:—

Figure 1 is a perspective view of a reamer embodying my invention.

Fig. 2 is a vertical longitudinal section of the same.

Fig. 3 is a transverse section on the line 3—3 of Fig. 2.

Fig. 4 is a longitudinal section showing a modified form of construction.

Fig. 5 is a transverse section on line 5—5 of Fig. 4.

Figs. 6 and 7 are detail views showing modified forms of cutting members adapted for use with the devices shown in Fig. 4.

Referring to the details of the drawing as 40 set out in Figs. 1 to 3, inclusive, the reference numeral 25 designates the body of a bit holder, cylindrical in form, having a reduced portion or neck 26 at the rear end, and furnished with a central bore 27 extending 45 entirely through the holder. The body of the holder is reduced to form a flange or shoulder 28 adjacent to the neck end 26, and surrounding said body and resting at one end against said flange or shoulder is a retaining sleeve 29. This retaining sleeve 50 is provided in its periphery with an annular series of channels or grooves 30, cylindrical in form, and having their outer sides open to the periphery of the ring. These grooves 55 30 extend entirely through the ring from end to end thereof, and within said grooves

are located cylindrical cutting elements or bits 31, each having a suitable longitudinal groove or channel 32 upon one side, so formed as to leave a salient lip 33 which 60 forms the cutting edge of the bit.

The cutting elements 31, which are rotatably mounted in the seat channels or grooves 29, are held in their seats or channels from lateral displacement by the overhanging of the curved walls of said channels and are retained from longitudinal displacement by a retaining nut 34 which is in threaded engagement with the upper end of the holder and engages the adjacent end of 70 the sleeve. This nut 34 is provided with a flange 35 which overhangs the forward ends of the cutters 31 and holds them from outward longitudinal movement, and said collar is also provided with sockets or recesses 36 75 whereby it may be engaged and adjusted by means of a spanner or similar tool. Between the flange or abutment 28 and the adjacent end of the sleeve 29 and rear ends of the cutters 31 is interposed an adjusting 80 collar or thimble 37 provided with elongated radial slots 38 engaged by decentered or eccentrically arranged pins 39 fixed in the rear ends of the cutters, whereby upon turning or rotating the collar or thimble the cutters may be turned or rotated to simultaneously project their cutting edges to a greater or less degree, the elongated slots allowing for the movement of the collar and pins upon the cutters through arcs of different 90 radii. The collar is provided with sockets 40 for the reception of a spanner, whereby the cutters may be conveniently adjusted.

It will be understood from the foregoing that the cutters are normally clamped in 95 adjusted position by the retaining nut 34, but that upon loosening said nut the adjusting collar or thimble may be turned to simultaneously rotate the cutters, and that after the cutters have been adjusted to a desired 100 degree the said cutters and adjusting collar may again be clamped or locked in adjusted position by tightening the nut 34. The slots and pins provide cam or eccentric mechanism for adjusting the cutters, as will be 105 readily understood.

The modification shown in Figs. 4 and 5 employs a body 25 and a sleeve 29 similar to those described in connection with Figs. 1, 2 and 3, the sleeve being retained by a collar 34' engaging the threads 41 on said body. An adjusting collar 42 is located be-

tween the sleeve 29 and the flange or shoulder 28. This collar has a marginal annular rim or flange 43 projecting from its upper or front face and within this rim are located a series of pins 44 which engage slots 45 attached to or formed integral with the cutters 31. The pins 44 may be arranged to engage slots in the body portions of the cutters, suitable slots for this purpose being shown in Figs. 6 and 7 at 47 and 48, respectively. The slots in the foot blocks are arranged at an angle to the axis of the device and coöperate with the pins to provide cam or eccentric mechanism for adjusting the cutters.

I claim:

1. In a reamer, the combination of a holder, cutters rotatably mounted upon the holder and provided with grooves forming cutting edges, and cam mechanism independent of said grooves for simultaneously rotating and adjusting the cutting elements.
2. In a reamer, the combination of a holder, a series of cutters rotatably adjustable upon the holder provided with grooves forming cutting edges, a rotary adjusting element, and cam mechanism independent of said grooves and actuated by said element for adjusting the cutters.
3. In a reamer, the combination of a holder, cutters rotatably mounted upon the holder and provided with grooves forming cutting edges, a rotatable adjusting element, and connecting means between the cutters and rotatable adjusting element, comprising pin and slot connections independent of said grooves, for adjusting said cutters upon the rotation of said elements.
4. In a reamer, the combination of a holder, a series of cutters rotatably adjustable upon the holder and provided with grooves forming cutting edges, a rotatable adjusting element, and connecting means between the cutters and the rotatable adjusting element comprising cam slots and pins independent of said cutting edges; said connecting means serving upon the rotation of the adjusting element to rotatably adjust the cutters.
5. In a reamer, the combination of a holder, a series of rotatably adjustable cutting elements, eccentrically arranged pins upon said cutting elements, and a rotary

adjusting member provided with means for engaging and actuating said pins.

6. In a reamer, the combination of a holder, a series of rotatably adjusting cutting elements, eccentric pins upon the cutting elements, and a rotary adjusting device provided with slots to receive and engage said pins.

7. In a reamer, the combination of a holder provided with peripheral seats, a series of cutting elements rotatably mounted in said seats, said cutting elements being provided with grooves forming cutting edges, a rotatable adjusting member, and a cam actuated by said member independent of connection with said grooves or cutting edges for adjusting said cutting elements.

8. In a reamer, the combination of a holder provided with peripheral seats, a series of cutting elements rotatable upon their axes in said seats, and said cutting elements being provided with grooves forming cutting edges, an adjusting member on the holder, and cam connections, wholly independent of said grooves and cutting edges of the cutting elements between said adjusting member and the cutting elements for rotatably adjusting the latter.

9. In a reamer, the combination of a holder provided with peripheral seat grooves, cutters freely revoluble on their axes in said grooves and provided with grooves forming cutting edges, a rotary actuating member mounted on the holder in proximity to one end of the cutters, and cam connections between said actuating member and the adjacent ends of the cutters, wholly independent of the cutting edges of the cutters for simultaneously rotating said cutters on their axes.

10. In a reamer, the combination of a holder provided with peripheral seats, cutters mounted in said seats and freely revoluble on their axes therein, a rotary actuating member upon the holder in proximity to one end of the cutters, said member being provided with cam slots and cam pins upon the adjacent ends of the cutters movable in said slots, whereby the cutters may be simultaneously rotated by movements of the ring.

In testimony whereof I affix my signature.

WILLIAM H. FRICK.
